UNITED STATES PATENT OFFICE.

OTTO BRINTZENHOFE, OF CLEVELAND, OHIO, ASSIGNOR TO ELECTRIC VACUUM CLEANER COMPANY, INC., OF CLEVELAND, OHIO, A CORPORATION OF NEW YORK.

SWIVEL CASTER.

Application filed October 11, 1923. Serial No. 667,851.

To all whom it may concern:

Be it known that I, OTTO BRINTZENHOFE, a citizen of the United States, residing at Cleveland, in the county of Cuyahoga, State 5 of Ohio, have invented certain new and useful Improvements in Swivel Casters, of which the following is a specification.

The present invention relates to swivel casters especially for vacuum cleaners.

10 The ordinary vacuum cleaner is provided with a pair of wheels located at the front end thereof and a caster at the rear which in some cases is fixed in position with respect to the cleaner and in other cases is swiveled, the 15 latter being preferable. As the cleaner is moved back and forth over the surface to be cleaned, the fork carrying the caster turns on its vertical axis so that the caster is always in a trailing position. This reduces the 20 labor of operating the same especially in passing over rugs and other uneven surfaces. The constant working back and forth of the caster as the cleaner is operated, tends to loosen the caster support and also to rather rapidly wear the moving parts which is 25 of course, objectionable.

30 My invention has for its object to improve the construction of such swivel casters to the end that they may be securely fastened to the cleaner and remain so, to provide ample bearing surfaces so that the caster will not be cramped or twisted out of line while 35 in use and to construct the parts in such a way that they are cheap to manufacture, light in weight and are interchangeable and this without the use of expensive machinery.

40 For a consideration of what I believe to be novel and my invention, attention is directed to the accompanying description and the claims appended thereto.

45 In the drawing which illustrates one of the embodiments of my invention, Fig. 1 is a view in elevation of a vacuum cleaner provided with my improved caster; Fig. 2 is a view partly in section of the caster and its supporting bracket, Fig. 3 is a section taken on line 3—3 of Fig. 2, and Fig. 4 is a detail view showing the means for uniting certain 50 of the parts.

55 5 indicates a vacuum or suction cleaner in which 6 is the nozzle, 7 the fan casing and 8 the high speed driving motor the casing of which fits into the fan casing at one end and has a hemispherical surface at the other end. 9 indicates the front floor wheels of

which two are provided, one on each side, and 10 the rear swivel caster. The cleaner is moved about by the handle 11, the lower end of which has a fork that straddles the cleaner and is suitably pivoted as at 12. 13 indicates the dust bag into which dirt etc. is discharged by the action of the fan.

As the rear end of the motor casing is hemispherical it is difficult to fasten the cast- 65 er thereto in such manner as to ensure its permanent fastening. To accomplish this the supporting bracket is made in two pieces 14 and 15. These have the same radius of curvature as the casing when viewed in side elevation and they are slightly curved in 70 cross section as indicated in Fig. 3 to conform to the curvature of the casing in a plane perpendicular to the axis of the motor. By preference these are made of sheet metal stampings. This ensures accuracy and 75 cheapness of manufacture. To prevent the bracket members from twisting one on the other which would throw the caster spindle out of line, one of said members is provided with side flanges 16 which engage the sides of the other member. Preferably but not necessarily, these flanges are continuous so as to afford long bearing surfaces. To state the matter another way, the bracket is made of two overlapping pieces which are in contact with each other for a portion of their length and at one end are separated to receive and hold a bearing sleeve, the channel-shaped section of one of the members preventing relative twisting movements.

The two members where they project be- 80 yond the motor casing are separated or spaced to form a fork or jaw to receive the bearing sleeve 17. The points of attachment of the members to the sleeve should be sufficiently separated to form a firm support for the sleeve to prevent rocking or twisting in a vertical plane. The upper end of the bearing sleeve is provided with a shoulder on which the horizontal end of the bracket member 14 is seated. These parts are united by means of a small tubular extension 18 which is rolled over or riveted. The lower end of the sleeve passes entirely through the horizontal part of the lower member 15 for a short distance and said member is pre- 85 vented from slipping off by the small upset portions 19, Fig. 4. The lower end of the sleeve also forms a thrust bearing for the caster spindle, the upset portions being

above the bearing surface. The sleeve is provided with an oil hole 20 through which both the vertical and thrust bearings of the caster spindle may be lubricated. The bracket and its caster are secured to the motor casing by two screws 21 which pass through both members into the casing. Under the head of each screw is a lock washer, and preferably the screws are body bound in the bracket.

22 indicates a spindle for the caster which is held in place at its upper end by a spring ring 23 which snaps into a groove therein. At the lower end of the spindle is a thrust bearing plate 24 and engaging therewith is a stamped metal fork 25 for the wheel 10. The fork is held in place by riveting over the reduced lower end of the spindle.

What I claim as new and desire to secure by Letters Patent of the United States, is:—

1. In a caster, the combination of a wheel, a supporting fork therefor, a spindle, a bearing sleeve for the spindle, and a bracket for the sleeve comprising a pair of members 28 which are spaced apart at one end to embrace the sleeve and are in interlocked relation at the other.

2. In a caster, the combination of a wheel, a supporting fork therefor, a spindle, a supporting bracket comprising a pair of members which are in contact for a portion of

their length and are spaced apart at one end, one of said members having projections engaging the other to prevent relative twisting of the members, and a bearing for the spindle which is held by the spaced ends of the members.

3. In a caster, the combination of a wheel, a supporting fork therefor, a spindle, a bracket comprising a pair of members which are interlocked at one end and are in spaced relation at the other, a bearing sleeve for the spindle which is riveted to the spaced end of one member and extends through the other, said sleeve being upset to prevent removal of the second member.

4. In a caster, the combination of a wheel, a supporting fork therefor, a spindle, a bracket comprising a pair of punched sheet metal members, one of which has flanges engaging the sides of the other, said members conforming in shape to the bracket support for a portion of their length at one end and being in spaced relation at the other, and a sleeve which is held by the spaced ends of the members to form a vertical bearing for the spindle and also a thrust bearing therefor at one end.

In witness whereof, I have hereunto set my hand this third day of October, 1923.

OTTO BRINTZENHOFE.
